Primary Examiner — Eric Goodman*Assistant Examiner* — Clese Moore, Jr.(74) *Attorney, Agent, or Firm* — Crowell & Moring LLP(57) **CLAIM**

The ornamental design for a chassis fairing for a highway truck, as shown and described.

DESCRIPTION

This application contains subject matter related to the following co-pending U.S. design patent application:

Application Ser. No. 29/432,195, filed herewith and entitled "Vehicle, Toy, and/or Replicas Thereof".

FIG. 1 is a left perspective view of a chassis fairing for a highway truck according to our design;

FIG. 2 is a right perspective view thereof;

FIG. 3 is a front view thereof; and,

FIG. 4 is a left perspective view thereof showing a possible environment.

The broken lines shown illustrate portions of the chassis fairing for a highway truck that form no part of the claimed design.
